ELECTRICAL AND OTHER CONNECTERS

Albert C. Hessel, New York, N. Y., assignor to
 W. F. Hessel Company, Inc., New York, N. Y.,
 a corporation of New York

Application April 12, 1934, Serial No. 720,295

8 Claims. (Cl. 173—363)

My invention relates to improvements in cable connectors and the like, and while adapted to many uses is especially suited for coupling electric lines,—particularly cables of high amperage capacity.

Briefly and generally, the invention aims to provide a simple, safe, cheap, easily assembled and highly efficient device of this character which comprehends interior members (which may constitute an electrical conductor),—and an exterior separable-section housing which is preferably in part carried by each interior member, there being novel and preferably substantially enclosed and protected securing means associated with the housing for holding all parts assembled.

A further and more specific object of the invention is to furnish an electrical connector comprising separable conductor and housing elements, wherein a housing section is carried by each conductor section, and wherein at least one securing element for attaching a conductor section to a housing section may be operated to lock the complete conductor and housing assembly together to form a unit,—the nature of the housing construction and locking means being such as to relieve the conductor from strain, which would tend to diminish its electrical efficiency.

The invention also resides in certain novel features of construction, combination and arrangement of the various parts and in modes of operation,—all of which will be readily understood by those skilled in the art upon reference to the following descriptive matter in connection with the accompanying drawing forming a part of this specification.

In accordance with the patent statutes, the drawing and descriptive matter have been directed to what now appear to be preferred embodiments of the inventive concept. But it is to be understood that the invention is susceptible of other mechanical expressions within the spirit and scope of the subject matter claimed herein-after.

In the drawing, wherein the same reference characters have been used to designate the same parts in all views,—

Figure 1 is a side elevational view of a connector embodying my invention;

Figure 2 is a longitudinal sectional view through the device;

Figure 3 is a longitudinal sectional view taken through a modified form of the invention, wherein in the housing is provided by interfitting dissimilar sections instead of by complementary duplicate sections as shown in Figures 1 and 2;

Figure 4 is a cross-sectional view taken through the device of Figure 3;

Figure 5 is a cross-sectional view illustrating a further modification of the invention, which is similar to Figures 1 and 2, except that an automatically operable locking element is employed in place of the screw or screws 15 of Figure 2;

Referring to Figures 1 and 2, numerals 8, 9 designate the pin and socket sections of an electrical conductor, the section 8 having the pin 10 extension 8^a fitting into the socket 9^a of conductor section 9. This is conventional construction in power line connectors, it being observed that each of sections 8, 9 has an end recess 10 within which the terminals (not shown) of cables 15

11 may be soldered or otherwise secured.

As shown, the sectional conductor 8, 9 is provided with a protective housing comprehending interfitting duplicate sections 12. Each section 12 has a tubular outer end portion 12^a, or the equivalent, for slidably receiving the outer end of one of the conductors 8, 9, which is locked therein by a screw 15 as will be more fully explained hereinafter. The inner, and preferably major, part of each housing section 12 takes the form of a halved tube, having lugs or tongue extensions 14 at its end. The inner ends of tubular portions 12^a provide notches or seats 13 for receiving lugs 14, when sections 12 are tracked together to form the tubular housing or closure for conductor 8, 9 as indicated in Figure 1. From the disclosures of Figures 1 and 2, it will be plain that the interfitting of the respective lugs 14 into recesses 13 will lock housing sections 12 together, except against relative longitudinal movement.

In the form of invention shown in Figures 1 and 2 the screws 15, which lock the respective conductor sections 8, 9 in the tubular end 12^a of its housing section 12, may be availed of selectively or in unison to lock the housing sections 12 against longitudinal movement relatively of one another. This arrangement will now be described.

As shown in Figure 2, each connector section 8, 9 is shown provided with a machine screw 15 working transversely therethrough, there being a counter-bore 17 for receiving the screw head 15^a. The outer end of such screw 15 is received in a hole 16, preferably located in the halved portion of its housing section 12 so as to hold the outer end of conductor 8 (or 9) in the tubular housing part 12^a. Thus, each connector section 8, 9 will be held in assembly with its housing section 12.

When the housing and connector assemblies 55

12, 8 and 12, 9 are interfitted, as shown in Figure 2, an inner counter-bored portion 18 of an opening 18^a in one housing section 12 will be arranged in registry with the counter-bore 17 of the connector 8 or 9 to which the other housing section 12 is attached. The screws 15 are made sufficiently long so that the heads 15^a can be backed into the aligned counter-bore 18 of one housing section 12, while still leaving a portion 10 of the opposite end projecting into the hole 16 of the companion housing section, as shown at the right in Figure 2. In fact, the depth of the housing counter-bore 18 in relation to the length of screws 15 will preferably be such as to prevent retraction of the outer ends of screws 15 from the holes 16. The openings 18^a, as will be evident, are for the admission of a screw driver for manipulating screws 15.

An important point to be noted is that the connector sections 8, 9 have, per se, no interlocking elements; also, that the connection of conductor sections 8, 9 through the housing 12, 12 substantially relieves the conductors 8, 9 from strain. All of this greatly promotes the electrical efficiency of the conductor. Referring to the form of invention shown in Figures 3 and 4, the conductor sections 20, 21 are adapted to interfit as indicated at 21^a the same as in Figure 2. The protective housing comprises dissimilar interfiting tubular sections 22, 23,—the former secured to conductor section 20 by screw 24, and the latter to conductor section 21 by screw 25. The reduced boss-like inner end 22^a has a lineal rib 22^b working in the mating groove 23^b in the counter-bored, or socket portion 23^a of housing section 23. This rib and groove formation 22^b, 23^b not only serves to align the diametrically enlarged inner end 27 of the transverse housing passage 27^a of section 23 with a corresponding passage 22^c of housing section 22, within which latter is head 24^a of screw 24,—but also reinforces and strengthens the sectional housing 22, 23.

The structure of Figures 3 and 4 differs from that of Figures 1 and 2 in that only one housing and conductor coupling screw, namely 24, is adapted to lock housing sections 22, 23 in assembly. Such screw 24 is adapted to be backed partially from hole 26 so as to actuate its head 24^a from housing passage 22^c into the aligned passage portion 27 of housing 23, so as to prevent relative lineal movement of housings 22, 23 and conductor sections 20, 21 carried thereby.

The coupling screw 25 which secures conductor section 21 to housing section 23 is insertable 55 through housing section hole 28, and takes in the threaded transverse bore of conductor section 21, with its inserted end adapted to project into the hole 26 of housing section 23 to lock the elements together.

60 Figure 5 discloses a spring actuated pin construction applied to a housing structure like that of Figures 1 and 2 comprising sections 30, 31 defining a cover for conductor sections, of which one is shown at 32. Conductor section 32, which corresponds to 8 of Figure 2 is carried by housing section 31 which has a tubular rear end (not shown) which receives the rear end of such conductor 32 just as 12^a receives 8 in Figure 2.

70 However, instead of having a tapped transverse bore like conductor sections 8 and 9 of Figures 1 and 2, the conductor section 32 of Figure 5 has a transverse bore 33 to slidably receive a pin 34, there being a counter-bore or enlargement 33^a receiving spring 39 and a shoulder 35^a of the pin. 75 A bushing 36 screwed into the outer end of coun-

ter-bore 33^a closes the outer end of the same. The rounded forward end of pin 34 extends through such bushing 36 to engage in an inner surface recess 38 of the adjacent housing section 30 when sections 30, 31 are fully tracked together like 5 housing sections 12, 12 of Figures 1 and 2. The length of pin 34 from shoulder 35^a to its rear end is such that the rear end of the pin 34 remains at all times at least partially projected into the recess 35 in the companion housing section 31, 10 so as to prevent the conductor section 32 from sliding out of the tubular end of its housing section 31. Use of pin structure 34, etc., enables the assembly to be automatically locked together by simply tracking housing sections 30, 31 together. 15 When they are to be separated it is only necessary to insert a pin or the like through hole 38 and against the rounded end of connector pin 34 to back same against spring 39, and at the same time pull housing sections 30, 31 apart. 20

It is believed that the operation of the devices disclosed in the various figures of the drawing will be readily apparent from the foregoing description. The housings will preferably be of fibre, rubber, wood or of phenol condensation product composition, and will necessarily be of same when the device is designed for use as an electrical connector. While the rib and groove constructional feature 22^b, 23^b is shown only in Figures 3 and 4; the automatically operating locking pin 34 30 only as applied to the housing structure of Figure 5 which is similar to that of Figures 1 and 2; yet it will nevertheless be apparent that these features may be utilized interchangeably in the illustrated and other embodiments of the invention. 35

The screws such as 15, 24, 25 will preferably be of metal, but may be of other materials; and the same applies to the locking pin 34 of Figure 5. Pin 34 is especially suited for formation from insulating material such as a phenol condensation product and in many instances it may be very desirable to use such material.

As indicated earlier herein, the illustrated embodiments of the invention are to be taken merely as illustrative of preferred expressions of the 45 invention. For instance, within the scope of the claims, the means such as 15, 24, etc., for preventing relative endwise shifting of the housing sections may lockingly engage the same without going through or even into the conductor elements 50 such as 8, 9 or 20, 21,—and the latter may be otherwise secured to housing sections.

The assembled housing and connector sections in pairs makes the device safe and convenient to use; and since the housing locking elements 15, 55 24 are substantially enclosed and protected the device is very durable. Housing locking elements such as 15, 24 whether going through conductors, such as 8, etc., or not, are considered desirable over such constructions as exterior clips seated in 60 a groove of adjacent housing sections as locking means. Referring to Figure 2, screws 15 may be threaded into holes 16 of the housing sections in which event the tubular housing ends 12^a for seating conductors 8, 9 would be unnecessary and the 65 transverse bores in conductors 8, 9 would not need to be tapped.

The term cable, as used in the foregoing specification and in the following claims, is to be construed as covering rods, shafts, etc. 70

Having thus described my invention, what I claim as new and desire to secure by Letters Patent is:

1. In an electrical connector having a pair of interfiting conductor bar sections, a substantially 75

tubiform housing comprising separable sections, having lineally extending overlapping interfitting parts, means securing each housing section to a different one of said conductor bar sections when the housing sections are disassembled, the securing means of at least one pair of said connected housing and conductor sections comprising a lineally movable pin-like member arranged in opposition to an overlapping portion of the other housing section, said overlapping portion of said last-mentioned housing having a pin-receiving recess, and one of said housing sections providing means whereby said pin may be operated.

2. In an electrical connector having a pair of interfitting conductor bar sections, a substantially tubiform housing comprising separable sections, having lineally extending overlapping interfitting parts, means securing each housing section to a different one of said conductor bar sections, the securing means of at least one pair of said connected housing and conductor sections including a pin yieldably bearing against an overlapping portion of the other housing section, said overlapping portion of said last-mentioned housing having a pin-receiving recess, and one of said housing sections providing means whereby said pin may be released from said recess.

3. In an electrical connector having a pair of interfitting conductor bar sections, a substantially tubiform housing comprising separable sections, having lineally extending overlapping interfitting parts, means securing each housing section to a different one of said conductor bar sections, the securing means of at least one pair of said connected housing and conductor sections comprising a lineally movable pin-like member arranged in opposition to an overlapping portion of the other housing section, said overlapping portion of said last-mentioned housing having a pin-receiving recess, reinforcing means for said housing comprising a lineally extending tongue and groove construction provided by said sections and whereby the same may be tracked together to align said pin and recess, and one of said housing sections providing means whereby said pin may be operated.

4. A cable connector or the like, comprising a pair of cable terminal members, a pair of interconnectible housing sections, means connecting at all times one housing section to one terminal member and the other housing section to the other terminal member, at least one of said housing section-and-terminal-connecting means including a transversely movable pin, and means including said transversely movable pin for locking said housing sections together and the terminal members in contact with one another.

5. A cable connector or the like, comprising a

pair of cable terminal members, a pair of interconnectible housing sections, means connecting at all times one housing section to one terminal member and the other housing section to the other terminal member, at least one of said housing section-and-terminal-connecting means including a transversely movable screw threaded through the terminal member, and means including said transversely movable screw for locking said housing sections together and the terminal members in contact with one another.

6. A connector for electric cables and the like, comprising interengageable conductor sections, separate housing sections having portions arranged to overlap when the housing sections are assembled, said overlapping housing portions having their inner surfaces providing opposed seats, means detachably connecting one housing section to one conductor section and the other housing section to the other conductor section, at least one of said housing and conductor section-connecting means including a transversely movable pin carried by one conductor section and having an end constantly engaging in the seat of its connected housing section, the overlapping housing portions having means to prevent relative shifting of the assembled housing sections in the direction of the axis of said pin, and said pin being movable into the seat of said second housing section to lock the housing and conductor section assemblies rigidly together.

7. An electrical connector comprising a separable section conductor bar, a housing therefor and comprising separable sections carried by the respective conductor bar sections, said housing sections having overlapping portions, the overlapping portion of each housing section having a shoulder at its inner end and providing a seat, a lug extension formed at the opposite end of each of said overlapping housing portions and engageable in the shoulder seat of the other housing section when the housing sections are tracked together, means including a transverse pin connecting one conductor bar section to its housing section, and a recess in the other housing section and receiving said pin whereby to lock housing sections in assembly.

8. An electrical connector comprising a separable section conductor bar, a housing therefor and comprising separable sections carried by the respective conductor bar sections, coupling means for said housing sections and including a substantially internally located but exteriorly operable transversely movable pin, and said pin having a constant connection with one housing section and its conductor section in all positions for securing the same together.

ALBERT C. HESSEL.
